FUEL CONTROL APPARATUS FOR INTERNAL-COMBUSTION ENGINES

Filed April 23, 1946

UNITED STATES PATENT OFFICE

2,667,743

FUEL CONTROL APPARATUS FOR INTERNAL-COMBUSTION ENGINES

Leighton Lee II, Rocky Hill, Conn., assignor, by
mesne assignments, to Niles-Bement-Pond
Company, West Hartford, Conn., a corpora-
tion of New Jersey

Application April 23, 1946, Serial No. 664,411

22 Claims. (Cl. 60—39.28)

1
The present invention applies to fuel control apparatus for internal combustion engines of the turbo-jet type, including gas turbine engines, jet engines, and combination gas-turbine-and-jet engines.

The particular embodiments of the invention herein disclosed are intended for control of fuel delivery to an internal combustion engine of the turbo-jet type suitable for propeller-propulsion, jet-propulsion, or combined propeller-and-jet propulsion of aircraft. Such engines usually include one or more combustion chambers, a compressor for supplying air to the combustion chambers, a fuel pump for supplying fuel to the combustion chambers, a gas turbine operated by the products of combustion from the chambers, and a tail pipe for discharging the gases from the turbine.

Owing to structural and metallurgical limitations of such engines, it is necessary to limit fuel flow to prevent speeds or temperatures in excess of predetermined values. The significance of the fuel-to-air ratio applying to reciprocating engines is less apparent in gas turbine engines, owing to the need of speed and temperature controls and the fact that relatively low values of the fuel-to-air ratio are employed. Nevertheless, gas turbine engines have definite fuel requirements, which are determined to some extent empirically, and mechanical means for satisfying such requirements must be developed.

An object of the present invention is to provide improved apparatus for controlling the supply of fuel to a gas turbine or turbo-jet engine.

Another object of my invention is to provide improved control apparatus for an internal combustion turbo-jet engine wherein a high pressure region of the engine is used as a source of fluid under pressure for operating a pressure responsive fuel flow controlling device, and the pressure of the fluid from that source may be modified in accordance with various other controlling conditions before the fluid is applied to said fuel flow controlling device.

It is a further object of my invention to provide improved apparatus for regulating fuel flow as a function of an air pressure derived from an air pressure differential which in turn is a function of engine speed, air density, and compressor characteristics.

Another object of my invention is to provide in control apparatus of the type described, improved means for limiting fuel flow so that predetermined engine speed and temperature limits will not be exceeded.

2
A further object of my invention is to provide, in an engine of the type described, improved means whereby auxiliary combustion means in the engine is made operable when predetermined conditions of engine operation exist.

A still further object of the present invention is to provide improved fuel control apparatus of simplified design in which an hydraulic motor for controlling pump delivery is operated by the pump discharge pressure so as to be self-regulating.

Other objects and advantages of the present invention will become apparent from a consideration of the appended specification, claims, and drawing, in which the figure illustrates, somewhat diagrammatically, one form of fuel control apparatus embodying the principles of my invention and its relation to the engine.

Referring to the drawing, there is shown diagrammatically an internal combustion engine of the turbo-jet type connected to a fuel control apparatus. Principal elements of the engine include an air inlet 10, a multi-stage air compressor generally indicated at 12, and a combustion chamber 14 supplied with fuel thru a series of nozzles 16 which are connected to a fuel manifold 18 into which the fuel is supplied thru a conduit 20 connected to the fuel control apparatus. An auxiliary fuel manifold 22 to which fuel is supplied by an auxiliary fuel conduit 24 is connected to one or more auxiliary nozzles similar to nozzles 16 in combustion chamber 14. Thus conduits 20 and 24 supply fuel to separate parallel nozzles. Gases leaving the combustion chamber 14 enter a turbine generally indicated as 26 and are discharged from the engine thru a tail pipe 28. A revolving shaft 30 is supported by a center bearing 32 and by end bearings 34 and 36 respectively at the outer ends of the compressor rotor 38 and the turbine rotor 40. A speed reducing gear train 42 connects the turbine shaft 30 with a propeller 44. In engines not used for propeller-propulsion the propeller is eliminated, the gear train is modified for driving accessories 45 only and turbine 26 is reduced to the capacity required to operate compressor 12 and accessories which include a generally indicated fuel pump 46 and a speed governor mechanism 48.

Fuel enters pump 46 thru an inlet conduit 45 connected to a source of supply such as a tank and is discharged from the pump into a conduit 50 from which it flows thru a metering orifice 52 into conduit 20 which carries fuel direct to the engine by way of manifold 18. A conduit 54 leads from conduit 20 to conduit 24 by way of an

auxiliary valve mechanism 56, for flow of fuel to the auxiliary manifold 22. The fuel control apparatus regulates the pressure differential across orifice 52 and thereby the total fuel flow to the engine thru both main and auxiliary systems.

In the fuel control apparatus there is shown a regulator generally indicated at 58 to which air is delivered from the discharge side of the compressor 12 thru a conduit 60, a thermal valve mechanism generally indicated at 62, a conduit 64, the governor mechanism 48, and a conduit 66. In the arrangement shown, air flows from regulator 58 thru a conduit 68 to a manually operated valve mechanism 70, thence either to atmosphere through a port 74, or alternatively, through a conduit 72 which is connected to air inlet 10 of the engine, upstream of compressor 12.

Regulator 58 has a generally cylindrical body in the ends of which are two symmetrically disposed chambers 76 and 78 which are separated by a centrally located constriction in said body, slideable in which there is a valve 80 having its ends extending into chambers 76 and 78 respectively. A movable plate 79 is fixed to the upper end of valve 80 and is attached to the lower and upper ends respectively of two bellows 82 and 84. The upper end of bellows 82 is fixed to the upper end of chamber 76, and the lower end of bellows 84 is fixed to the lower end of chamber 76. A sealing bellows 88 is mounted between plate 79 and the lower end of chamber 76, paralleling bellows 84 and forming therewith a chamber 87. A spring 86 is retained in compression between the plate 79 and the lower end of chamber 76. Conduit 66 is connected to the interior of bellows 82, the pressure in which is therefore the compressor discharge pressure whenever unrestricted flow occurs from conduit 60 to conduit 66. Chamber 76 is supplied with air flowing from conduit 66 thru a restriction 90 in a conduit 92. The pressure on the exterior of bellows 82 and 84 is that of air in chamber 76 and is therefore atmospheric pressure whenever unrestricted flow occurs from chamber 76 to conduit 72. Bellows 84 may either be evacuated or filled with a temperature responsive medium at a predetermined pressure and sealed before installation thereby rendering bellows 84 responsive to temperature and pressure changes in chamber 76.

In chamber 78, a bellows 94 is mounted between the lower end of valve 80 and the lower end of chamber 78. A conduit 96 connects the interior of bellows 94 to conduit 50 and a conduit 98 connects the chamber 78 to conduit 20, thereby rendering bellows 94 responsive to the fuel pressure differential across metering orifice 52.

In equilibrium, the upward force on valve 80 due to the fuel pressure differential acting on bellows 94 equals the net downward force at the upper end of valve 80, comprising forces due to air pressure differentials acting on bellows 82 and 84 and an upward force due to spring 86. At constant temperature and pressure in chamber 76, only the forces produced by bellows 82 and 94 vary, and therefore valve 80 is in equilibrium whenever the ratio between the air pressure differential acting on bellows 82 and the fuel pressure differential acting on bellows 94 is a predetermined constant. Thus, when the flow of air to and from regulator 58 is unrestricted and the temperature and pressure in chamber 76 are constant, the fuel pressure differential across metering orifice 52 is proportional to the compressor discharge pressure.

There is provided in the pump 46 a suitable means for varying the pump delivery, which may be of any conventional form such as that disclosed in U. S. Patent 2,093,477, Sept. 21, 1937, and is operable by a lever 100. A hydraulic motor, generally indicated at 102, has a piston 104 connected to lever 100 by a link 106. The piston 104 separates two expandable chambers 108 and 110. Chamber 110 is supplied with fuel at the pump discharge pressure by a conduit 113 connected to another conduit 120 which in turn is connected to conduit 50. Chamber 108 is supplied thru a conduit 113 with fuel at a motor pressure from regulator 58. A spring 114 imposes a downward force on piston 104 and biases the delivery varying means toward maximum delivery position. As the motor pressure increases, piston 104 is moved downward in opposition to the pump discharge pressure in chamber 110, thereby increasing the pump delivery and hence the discharge pressure until a position of equilibrium is obtained. Thus, the pump delivery and the pump discharge pressure are functions of the motor fuel pressure in conduit 113, and increase as the motor pressure increases.

Valve 80 as shown is one of a number of conventional forms which may be used and includes a recess 116, a port at the upper end of conduit 120, and a similar port at one end of a drain conduit 112 the other end of which is connected to inlet conduit 45. Both ports are closed when valve 80 is in its normal position. The pressure in conduit 112 is substantially constant; and, when valve 80 is in its normal position, the pump delivery is substantially constant. On downward movement from the normal position referred to, valve 80 permits fuel to flow from conduit 50, thru conduit 120, to conduit 113 and into chamber 108. Upon upward movement from the normal position, valve 80 permits flow from chamber 108, thru conduit 113, to drain conduit 112, and thence to the pump inlet conduit 45.

Thus as valve 80 moves in a downward direction, as when the compressor discharge pressure acting on bellows 82 increases, the motor fuel pressure increases, and the pump delivery increases and hence the pump discharge pressure increases. Conversely, as valve 80 moves in an upward direction, as when the compressor discharge pressure decreases or the fuel pressure differential across metering orifice 52 increases, the motor fuel pressure decreases, and the pump delivery and hence the pump discharge pressure decreases.

55. The fuel pressure differential across metering orifice 52 is normally proportional to the compressor discharge pressure in conduit 60 which acts on bellows 82, and the fuel flow is therefore a predetermined constant function of the compressor discharge pressure. As previously stated, this applies only at normal operating speeds and temperatures, when air lines to and from regulator 58 are unrestricted, and when auxiliary conduit 24 is inoperative.

65. The thermal control 62 comprises a tube 122 having its upper end closed, the control being so mounted that a portion of the tube extends into the engine where it is subjected to temperature of the gases in tail pipe 28. The other end of tube 122 is retained by a body 124 having an aperture 126 therein for passage of a rod 126 therethru, the upper end of rod 126 being fixed to the closed end of tube 122. The lower end of rod 126 bears a valve 132 which is operable in a seat 130 in body 124, seat 130 separating cham-

bers 131 and 133 upstream and downstream from valve 132 which are connected to conduits 60 and 64 respectively. The rod 126 and tube 122 are made of materials having substantially different coefficients of thermal expansion, so that, upon an increase in temperature adjacent tube 122, the tube expands faster than rod 126, thereby moving the valve 132 toward closed position and restricting flow from conduit 60 to conduit 64. By proper construction and dimensions of the parts, the thermal control may be made ineffective to control the flow of air therethru except within a relatively narrow range of temperature near the predetermined limiting temperature.

The governor mechanism 48 has a body 49 and employs a conventional fly-weight governor 129 operated from the gear train 42 in the engine. It is normally mounted in a position at right angles to that shown. An extension of body 49 has an opening therethru which serves as a guide for a governor valve 134. A contoured portion of valve 134 moves in a seat 136 thereby varying the flow of air from conduit 64 to conduit 66 which conduits are respectively connected to body 49 on opposite sides of seat 136. A spring 138 is placed between one end of valve 134 and a support 140 which is slidable in body 49. The other end of valve 134 is connected to the governor 129 so that valve 134 moves toward the right in opposition to spring 138 and restricts the flow from conduit 64 to conduit 66 as the governor speed increases. A channel 135 is used to equalize pressures at the ends of valve 134. It is thus apparent that as the governor speed varies and, hence as the engine speed varies, valve 134 varies the flow from conduit 64 to conduit 66, this flow decreasing as the engine speed increases. The rate of change of flow across valve 134 in respect to engine speed change is controlled by properly contouring the valve.

In valve mechanism 70 there is a valve 71, in a valve body 73, the valve being operable in a seat 75 to vary the flow from conduit 68 to conduit 72 or part 74. Valve 71 is connected to a manually-operated lever 77 and is also connected to a slidable spring support 140 in governor mechanism 48, by means of a link 81 and a lever 83 which is pivoted at a fixed support 85. In operation, as valve 71 is moved toward its seat, slidable spring support 140 is moved away from valve 134 thereby decreasing the spring force acting on valve 134 and allowing it to move toward seat 136 and to further decrease flow from conduit 64 to conduit 66.

The auxiliary valve mechanism 56 comprises a body 142 having a chamber 144 to the left-hand end of which is fixed one end of a bellows 146. Movement of the free end of bellows 146 is opposed by a spring 148, having one end supported by the bellows and the other end by the right-hand end of chamber 144. The interior of bellows 146 is connected by conduit 141 to the interior of regulator 68 at a source of motor pressure. An extension of body 142 is provided with a cylinder 150 which serves as a guide for a piston valve 152 having one end fixed to the movable end of bellows 146. The body 142 is apertured to connect conduits 24 and 54 with cylinder 150, and valve 152 has a grooved portion 154 near its mid-portion which is operable to permit restricted flow from conduit 54 to conduit 24 as valve 152 moves toward the right. A conduit 156 serves as a vent for cylinder 150 at the end of valve 152 and may be connected to inlet conduit

45. A channel 158 thru valve 152 equalizes the pressure in chamber 144 with that in conduit 156. Valve 152 is positioned by a force produced by the motor pressure acting on bellows 146 tending to open the valve, and by spring 148 which tends to close it. The spring is selected to keep the valve closed below a predetermined value of motor pressure.

In operation, the bellows 82 in regulator 58 is subject to an effective air pressure differential which is the differential between compressor discharge and atmospheric pressures, when the flow of air to and from the regulator is unrestricted. When the pressure and temperature in chamber 176 is constant, the main fuel flow thru conduit 20 is a function of this effective air pressure differential. To prevent excessive tail pipe temperature, it is necessary to reduce the fuel flow when a predetermined limiting temperature is reached; this is done by means of thermal control 62 which reduces the flow of air from conduit 60 to conduit 64 and thereby reduces the effective air pressure differential acting in regulator 58, as the temperature increases to a value at which thermal control 62 is effective. Similarly, to prevent excessive engine speed, it is necessary to reduce the fuel flow when a predetermined limiting speed is reached; this is done by means of the speed governor mechanism 48 which reduces the flow from conduit 64 to conduit 66 and thereby reduces the effective air pressure differential acting in regulator 58, as the speed increases to a value at which the governor mechanism is effective.

Manual control of the effective air pressure differential is accomplished by valve mechanism 70. In this case, the flow of air from regulator 58 is controlled; the effective air pressure differential and hence the fuel flow decrease as valve 71 closes, in the same manner that the effective differential and the fuel flow decrease as either valve 132 or valve 134 closes.

The governor mechanism 48 and manually-controlled valve mechanism 70 are connected, so that when lever 77 is operated it sets the governor valve spring 138 so that the governor becomes effective at a predetermined value corresponding to the position of lever 77. Simultaneously, the movement of lever 77 produces a change in the position of valve 71 in respect to its seat 75, so that as the predetermined limiting value of speed is increased, as by increasing the load of spring 138 on valve 134, the effective air pressure differential is increased by moving valve 71 toward its open position. The connection between the governor and the manual valve mechanism is for the purpose of limiting fuel flow to a fixed amount less than fuel flow required to produce limiting temperature at any value throughout the range of manual speed control. To accomplish this purpose, the design of governor mechanism 48 and that of valve mechanism 70 are coordinated in reference to such factors as valve contours, spring rates, governor characteristics, and linkage.

An additional temperature effect is produced by bellows 84 which tends to raise valve 80 as the temperature in chamber 176 increases, thereby reducing the motor pressure and the fuel flow. This supplementary temperature control is in effect a means whereby the compressor discharge pressure is temperature corrected so that the fuel flow is more nearly a function of the mass rather than the velocity of air flowing thru the engine. Supplementing the main fuel flow thru con-

duit 20, auxiliary valve mechanism 56 provides means of causing flow to the auxiliary fuel manifold 22 when a predetermined value of motor pressure or when a predetermined value of main fuel flow is attained.

In the foregoing illustrated and described embodiment of my invention, expansible bellows are employed for converting pressure differentials to working forces; in the appended claims, however, the term "bellows" is used in a general sense which embraces collapsible pressure-responsive elements such as diaphragms, movable pistons, or other suitable equivalent means.

While I have shown and described a preferred embodiment of my invention, it will be readily understood by those skilled in the art that other modifications may be made without departing from the scope of the invention as defined in the appended claims.

I claim as my invention:

1. Fuel control apparatus for a turbo-jet engine, having associated therewith a fuel conduit and a source of fuel at superatmospheric pressure, for delivering fuel to said engine, and means for varying the delivery from said source to said fuel conduit, comprising: hydraulic motor means responsive to a control air pressure derived from the difference between a plurality of fluid pressures in said engine, and means responsive to the speed of said engine for modifying said control air pressure whereby the fuel flow is a function of said difference in fluid pressures and said speed.

2. Fuel control apparatus for a turbo-jet engine, having associated therewith a fuel conduit for delivering fuel thereto, a source of fuel at superatmospheric pressure, and means for varying the delivery from said source to said fuel conduit, comprising: hydraulic motor means responsive to a control air pressure derived from the difference between a plurality of fluid pressures in said engine, and means responsive to the temperature of exhaust gases in said engine for modifying said control air pressure, whereby the fuel flow is a function of said difference in fluid pressures and said temperature.

3. Fuel control apparatus for a turbo-jet engine, having associated therewith a fuel conduit and a source of fuel at superatmospheric pressure, for delivering fuel to said engine, and means for varying the delivery from said source to said fuel conduit, comprising: fluid motor means responsive to a control air pressure derived from the difference between a plurality of fluid pressures in said engine, and manually-operated means for modifying said control air pressure whereby the fuel flow is a function of said difference in fluid pressures and said manual modification.

4. Fuel control apparatus for a turbo-jet engine, having associated therewith a fuel pump and conduit for delivering fuel thereto, said pump having delivery varying means associated therewith, comprising: hydraulic motor means responsive to fluid pressure supplied thereto and effective to control said delivery varying means, a metering orifice in said fuel conduit and means connected to said conduit effective to regulate said motor fluid pressure in response to the fuel pressure differential across said metering orifice and to an air pressure differential at least one component of which is derived from a pressure in said engine; whereby the fuel flow varies as a function of said air pressure in the engine.

5. Fuel control apparatus for a turbo-jet en-

gine, having associated therewith a fuel pump and conduit for delivering fuel thereto, said pump having delivery varying means associated therewith, comprising: hydraulic motor means responsive to a motor fluid pressure supplied thereto effective to control said delivery varying means, a metering orifice in said fuel conduit, means connected to said conduit effective to regulate said motor fluid pressure in response to the fuel pressure differential across said metering orifice and to an air pressure differential at least one component of which is derived from a pressure in said engine, and means for modifying said air pressure differential responsive to the speed of said engine, whereby the fuel flow varies as a function of said speed and said engine pressure.

6. Fuel control apparatus for a turbo-jet engine, having associated therewith a fuel pump and conduit for delivering fuel thereto, said pump having delivery varying means associated therewith, comprising: hydraulic motor means responsive to a motor fluid pressure supplied thereto effective to control said delivery varying means, a metering orifice in said fuel conduit, means connected to said conduit effective to regulate said motor fluid pressure in response to the fuel pressure differential across said metering orifice and to an air pressure differential at least one component of which is derived from a pressure in said engine; and means for modifying said air pressure differential in response to the temperature of exhaust gases in said engine, whereby the fuel flow varies as a function of said temperature and said engine pressure.

7. Fuel control apparatus for a turbo-jet engine, having associated therewith a fuel pump and conduit for delivering fuel thereto, said pump having delivery varying means associated therewith, comprising: hydraulic motor means responsive to a motor fluid pressure supplied thereto effective to control said delivery varying means, a metering orifice in said fuel conduit, means connected to said conduit effective to regulate said motor fluid pressure in response to the fuel pressure differential across said metering orifice and to an air pressure differential at least one component of which is derived from a pressure in said engine; and manually-controlled means for modifying said air pressure differential, whereby the fuel flow varies as a function of said manual control and said engine pressure.

8. Fuel control apparatus for a turbo-jet engine, having associated therewith a fuel pump and conduit for delivering fuel thereto, said pump having delivery varying means associated therewith comprising: hydraulic motor means responsive to a motor fluid pressure supplied thereto effective to control said delivery varying means, a metering orifice in said fuel conduit, means connected to said conduit effective to regulate said motor fluid pressure in response to the fuel pressure differential across said metering orifice and to an air pressure differential at least one component of which is derived from a pressure in said engine; first and second means respectively for modifying said air pressure differential in response to engine speed and the temperature of exhaust gases flowing thru said engine, and manually-controlled third means for modifying said air pressure differential, whereby the fuel flow varies as a function of said engine air pressure, said speed, said temperature, and said manual control.

9. Fuel control apparatus for a turbo-jet engine, having associated therewith a fuel pump

and conduit for delivering fuel thereto, said pump having delivery means associated therewith, comprising: hydraulic motor means responsive to a motor fluid pressure supplied thereto effective to control said delivery varying means; a metering orifice in said fuel conduit, a first bellows responsive to the fuel pressure differential across said orifice, a second bellows responsive to an air pressure differential at least one component of which is derived from said engine, a value operated by said first and second bellows for regulating said motor pressure, whereby the fuel pressure differential across said orifice and hence the fuel flow to the engine are functions of said air pressure differential.

10. Fuel control apparatus for a turbo-jet engine, having associated therewith a source of fuel at superatmospheric pressure, a conduit for conveying fuel from said source to said engine and means for varying the fuel delivery from said source to said conduit, comprising: conduit means for deriving an air pressure differential from an air pressure in said engine; means regulating said delivery varying means in response to said air pressure differential; first means in said conduit means responsive to the speed of said engine and effective to modify said air pressure differential, and a manually-operated control in said conduit means effective to modify said air pressure differential in series with said first modifying means, whereby the fuel flow varies as a function of said engine pressure differential, said speed, and said manual control.

11. Fuel control apparatus for a turbo-jet engine, having associated therewith a source of fuel at superatmospheric pressure, a conduit for conveying fuel from said source to said engine and means for varying the fuel delivery from said source to said conduit, comprising: conduit means for deriving an air pressure differential from an air pressure in said engine; means regulating said delivery varying means in response to said air pressure differential; first means in said conduit means responsive to the speed of said engine and effective to modify said air pressure differential, and second means in said conduit means responsive to exhaust gas temperatures in said engine and effective to modify said air pressure differential, said first and second modifying means being in series, whereby the fuel flow varies as a function of said engine pressure, said speed, and said temperature.

12. Fuel control apparatus for a turbo-jet engine, having associated therewith a compressor for delivering combustion air thereto, a source of fuel at superatmospheric pressure, a conduit for conveying fuel from said source to said engine and means for varying the fuel delivery from said source to said conduit, comprising: conduit means for deriving an air pressure differential from an air pressure in said engine; means regulating said delivery varying means in response to said air pressure differential; first valve means in said conduit means for modifying the high pressure component of said air pressure differential in response to the temperature of exhaust gases in said engine, second valve means in said conduit means responsive to the engine speed for modifying the high pressure component of said differential, fixed means in said conduit means for controlling said differential, and third valve means in said conduit means manually-operated to modify said differential, said first and second valve modifying means, said fixed means, and said third valve modifying means being in series,

whereby the fuel flow varies as a function of said engine pressure and said four modifying means.

13. Fuel control apparatus for a turbo-jet engine including an air compressor, and having associated with said engine a fuel pump and conduit for delivering fuel thereto, said pump having delivery varying means associated therewith, comprising: hydraulic motor means responsive to a motor fluid pressure supplied thereto effective to control said delivery varying means, conduit means for deriving an air pressure differential from the compressor discharge pressure in said engine, valve means regulating said delivery varying means in response to said air pressure differential, first means for modifying said differential in response to the temperature of exhaust gases in the engine, a speed governor, valve means responsive to said governor and fixed means for controlling said differential and manually-operated valve means for modifying said differential, said four modifying means being in series in said conduit means, a spring associated with said governor-operated means, and means connected to said manually-operated means for varying the deflection of said spring, whereby the fuel flow varies as a function of said compressor discharge pressure, said temperature, said speed, and said manually-operated valve means.

14. Fuel control apparatus for a turbo-jet engine having therein main and auxiliary burners and having associated therewith main and auxiliary fuel conduits respectively for delivery of fuel to said main and auxiliary burners, a compressor for delivering combustion air to said engine, a fuel pump and means for varying the delivery thereof, and a connection between said pump and said main and auxiliary conduits, comprising: conduit means for deriving an air pressure differential from the compressor pressure differential in said engine, a metering orifice in said main conduit, hydraulic motor means for controlling said delivery varying means in response to a motor fluid pressure supplied thereto, valve means for regulating said motor pressure in response to said air pressure differential, and to the fuel pressure differential across said metering orifice; at least two variable orifices in series in said conduit means effective to modify said air pressure differential; and second means responsive to said motor pressure effective to connect said auxiliary fuel conduit to said main fuel conduit downstream from said orifice when said motor pressure exceeds a predetermined value, whereby the total fuel flow varies as a function of said compressor pressure differential, said variable restrictions in series and said second conduit connecting means.

15. Fuel control apparatus for a turbo-jet engine including a tail pipe, and having associated with said engine a fuel conduit, a fuel pump, and means for varying the delivery of said pump to said conduit, comprising: conduit means for deriving an air pressure differential from a pressure in said engine, a metering orifice in said fuel conduit, an hydraulic motor effective to regulate said delivery varying means in response to a motor fluid pressure supplied thereto, valve means for regulating said motor pressure responsive to said air pressure differential and to the fuel pressure differential across said orifice, fixed means in said conduit means for controlling said air pressure differential effective to control the rate of response of said regulating means to said modified air pressure differential, and first and second valve means in said conduit means in series with

11

said fixed means effective to modify said air pressure differential in response to the speed of said engine and the temperature of gases in said tail pipe, whereby the fuel flow varies as a function of said engine pressure, said fixed controlling means, said engine speed and said tail pipe temperature.

16. Fuel control apparatus for a turbo-jet engine, including a tail pipe and an air compressor and having associated with said engine a fuel conduit, a fuel pump and means for varying the delivery thereof, and a connection between said pump and said conduit, comprising: hydraulic motor means responsive to a motor fluid pressure supplied thereto and effective to control said delivery varying means; conduit means for deriving an air pressure differential from the compressor pressure differential in said engine; an air bleed in said conduit means subjected to said air pressure differential, valve means regulating said motor pressure in response to said air pressure differential; first valve means upstream from said bleed for controlling the flow of air in said conduit means in response to the temperature of gases in said tail pipe, a governor connected to said engine, governor-valve means in series with said first valve means and upstream from said bleed for controlling the flow of air in said conduit means in response to said governor, a spring effective to regulate said response of said governor-valve to said governor, and a variable support for said spring; a manually-operated valve downstream from said bleed in said conduit means effective to control the flow of air therethru; and a connection between said governor spring support and said manually-operated valve; whereby the fuel flow varies as a function of said compressor pressure differential, the tail pipe temperature, the engine speed, and said manual control.

17. Fuel control apparatus for a turbo-jet engine, having associated therewith first and second fuel conduits and a compressor respectively for delivering fuel and combustion air thereto, and having also associated therewith a fuel pump and means for varying the delivery thereof, connections between said pump and said first and second conduits, and a tail pipe, comprising: a metering orifice in said first conduit, hydraulic motor means responsive to a motor fluid pressure supplied thereto and effective to control said delivery varying means; conduit means for deriving an air pressure differential from the compressor pressure differential in said engine, an air bleed in said conduit means subjected to said air pressure differential, valve means for regulating said motor pressure responsive to said air pressure differential and to the fuel pressure differential across said metering orifice; first valve means upstream from said bleed for controlling the flow of air in said conduit means in response to the temperature of gases in said tail pipe, a governor connected to said engine, governor-valve means in series with said first valve means and upstream from said bleed for controlling the flow of air in said conduit means in response to said governor, a spring effective to regulate said response of said governor-valve to said governor, and a variable support for said spring; a manually-operated valve downstream from said bleed in said conduit means effective to control the flow of air therethru, and a connection between said governor spring support and said manually-operated valve; an auxiliary valve, means responsive to said

12

motor pressure and effective to operate said auxiliary valve, said auxiliary valve being effective to connect said first and second conduits at a point downstream from said orifice when said motor pressure exceeds a predetermined value; whereby the total fuel flow varies as a function of the compressor pressure differential, the tail pipe temperature, the engine speed, said manual control, and said auxiliary valve.

18. Fuel control apparatus for a turbo-jet engine including a tail pipe and an air compressor, and having associated with said engine a fuel pump and conduit for the flow of fuel thereto, means for varying the delivery of said pump to said conduit, comprising: a metering orifice in said fuel conduit, an hydraulic motor effective to regulate said delivery varying means in response to a motor fluid pressure supplied thereto, a tube having its opposite ends connected to pressures in said engine upstream and downstream respectively from said compressor, a fixed restriction for controlling the flow of air therethru, first and second valve means for respectively varying the flow thru said tube in response to the engine speed and the temperature of gases in said tail pipe, manually-operated valve means for varying the flow in said tube in series with said other flow varying means, valve means regulating said motor pressure responsive to the differential between the pressure downstream from said compressor and the pressure in said tube on the upstream side of said manually-operated valve, said regulating valve means being also responsive to the fuel pressure differential across said orifice, whereby the fuel flow varies as a function of said upstream and downstream pressures and said means for varying the flow in said tube.

19. Fuel control apparatus for a turbo-jet engine, having associated therewith a fuel pump and means for varying the delivery of said pump to said engine, comprising: motor means responsive to a motor fuel pressure and to a motor air pressure and effective to control said delivery varying means, said motor fuel pressure being a function of the fuel pressure differential across said pump and said motor air pressure being a function of the difference between a plurality of fluid pressures in said engine, and means for varying said motor air pressure, whereby the fuel flow varies as a function of said fuel pressure differential, said difference in fluid pressures, and said pressure varying means.

20. Fuel control apparatus for a turbo-jet engine, having associated therewith a fuel pump and means for varying the delivery of said pump to said engine, comprising: motor means responsive to a motor fuel pressure and to a motor air pressure and effective to control said delivery varying means, said motor fuel pressure being a function of the fuel pressure differential across said pump and said motor air pressure being a function of the difference between a plurality of fluid pressures in said engine, and means for varying said motor fuel pressure, whereby the fuel flow varies as a function of said fuel pressure differential, said difference in fluid pressures and said motor fuel pressure varying means.

21. Fuel control apparatus for a turbo-jet engine, having associated therewith a fuel pump and means for varying the delivery of said pump to said engine, comprising: motor means responsive to a motor fuel pressure and to a motor air pressure and effective to control said delivery varying means, said motor fuel pressure being a function of the fuel pressure differential across

said pump and said motor air pressure being a function of the difference between a plurality of fluid pressures in said engine, and means for varying said motor fuel and motor air pressures, whereby the fuel flow varies as a function of said fuel pressure differential, said difference in fluid pressures, said motor fuel pressure varying means, and said motor air pressure varying means.

22. Fuel control apparatus for a turbo-jet engine, including an air compressor, and having associated with said engine a fuel pump and means for varying the delivery of said pump to said engine, comprising: motor means responsive to the compressor discharge pressure in said engine and effective to regulate said delivery varying means, a conduit effective to by-pass fuel therethru around said pump, a restriction in said conduit, a connection for the flow of fuel between said conduit upstream from said restriction to 10

15 20

said motor means, thereby rendering said motor means also responsive to the fuel pressure in said connection, whereby the fuel flow varies as a function of said compressor discharge pressure and said fuel pressure.

LEIGHTON LEE II.
